UNITED STATES PATENT OFFICE

EMIL STRANSZKY, OF PHILADELPHIA, PENNSYLVANIA.

MULTIPLE-FUSE PLUG.

1,127,106.

Specification of Letters Patent.

Patented Feb. 2, 1915.

Application filed July 7, 1914. Serial No. 849,555.

To all whom it may concern:

Be it known that I, EMIL STRANSZKY, a subject of the Emperor of Austria-Hungary, residing at Philadelphia, in the county of Philadelphia and State of Pennsylvania, have invented new and useful Improvements in Multiple-Fuse Plugs, of which the following is a specification.

This invention relates to improvements in 10 multiple fuse plugs for electric circuits.

In carrying out the present invention, it is my purpose to improve and simplify the general construction of multiple fuse plugs and to provide a plug whereby the fusible 15 elements may be connected in the electric circuit successively as the same become burnt out, thereby eliminating the necessity of removing the plug and inserting a new one.

It is also my purpose to provide a plug 20 of the class described which may be placed in the circuit rapidly and easily and which may be manipulated conveniently and quickly to place a new fusible element in the 25 circuit succeeding the burning out of one of such elements.

With the above and other objects in view, the invention consists in the construction, combination and arrangement of parts 30 hereinafter set forth in and falling within the scope of the claims.

In the accompanying drawing, Figure 1 is a view in side elevation of a multiple fuse plug constructed in accordance with the 35 present invention. Fig. 2 is a longitudinal sectional view therethrough. Fig. 3 is an end view of the body of the plug, the cap being removed. Fig. 4 is an end view of the cap. Fig. 5 is a similar view showing the 40 opposite end of the cap.

Referring now to the drawing in detail, 1 designates the body of the plug constructed of porcelain or other insulating material and preferably circular in cross section, one 45 end of the body being circumferentially reduced as at 2 and externally screwthreaded as at 3 so that the same may enter the socket or receptacle. Formed in the body 1 longitudinally thereof and centrally disposed is 50 a bore 4 through which is passed a shank 5 having one end formed with a head 6 in contact with the end portion of the reduced extremity of the body and forming a contact adapted to be connected to one side of an electric circuit, and the opposite end projecting beyond the adjacent extremity of 55

the body, while formed in the last-mentioned end of the body is an annular row of depressions 7 disposed concentrically of the shank 5. Loosely surrounding the projecting end of the shank 5 and capable of rotation thereon is a cap 8 composed of porcelain or other suitable insulating material and arranged concentrically of the shank and placed in face to face contact with the adjacent end of the body. On the inner 60 face of the cap 8 is an annular row of contact studs 9 disposed concentrically of the shank and fitting into the depressions 7, while formed in the outer face of the cap 8 centrally thereof is a recess 10 provided with a cup-shaped lining 16' having the outer edge thereof bent upon itself to provide an annular flange lying against the outer surface of the cap concentrically of 75 the recess and forming a conductor ring 11 with which are connected a number of fusible elements 12 radiating from such ring and having the outer ends thereof connected with the contact studs 9 respectively, the 80 fusible elements being embedded in the outer end or face of the cap 8. Threaded onto the extended end of the shank 5 and disposed within the recess 10 is a securing nut 13 while surrounding the shank within 85 the recess is a coiled expansion spring 14 having one end in engagement with the end wall of the recess and the opposite extremity abutting the adjacent face of the securing nut, such spring acting to hold the contact 90 studs seated in the recesses and force the studs into such recesses in the turning of the cap on the body. The outer surface of the circumferentially reduced end portion of the body 1 is preferably inclosed in a 95 metallic shell 15 adapted to connect with the other side of the electric circuit and threaded through the opening in the body is a contact screw 16 having one end electrically connected with the shell 15 and the 100 opposite end projecting into one of the depressions 9 so that the fusible element 12, connected with the stud seated within the particular depression will be connected in the electric circuit and whereby the fusible 105 elements may be connected in the electric circuit successively in the rotation of the cap.

From the foregoing description taken in connection with the accompanying drawing, the construction, mode of operation and 110 manner of employing my invention will be readily apparent. When the device is placed

in an electric circuit the contact formed by the head 6 engages one contact in the receptacle or socket, while the contact formed by the shell 15 engages the remaining contact 5 in the receptacle, current flowing through the shank 5, spring 14, lining 16 and ring 11 formed by the flanged edge of such lining, the particular fusible element connected with the stud in engagement with the contact screw 16, said stud and contact screw, and the shell. When the fuse in the circuit is burnt out the cap 8 is rotated to bring the next adjacent fuse into the circuit and in the initial movement of the cap, the latter 10 moves outwardly along the shank against the action of the spring 14, incident to the studs riding out of the depressions, and in the continued movement of the cap the studs reenter the depressions and a new fusible element is thus connected in the circuit in which the device is installed, the spring 14 reseating the studs when the latter register with the depressions. When the device is used to carry heavy currents, a wire is employed to connect the upper end of the shank 5 to the ring 11, as clearly illustrated in Figs. 2 and 5 of the drawing, such wire insuring the proper carrying of the current independently of the spring and lining.

30 While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

40 1. A multiple fuse plug comprising a body formed centrally with a longitudinal bore and having one end thereof formed with an annular row of depressions concentrically of the bore, a shank within the bore 45 having one end thereof provided with a head forming a contact adapted to be connected to one side of the electric circuit and the opposite end projecting beyond the end of the body having the depressions therein,

50 a cap surrounding the last-mentioned end of said shank concentrically thereof and rotatable thereabout and in face to face contact with the adjacent end of the body, an annular row of contact studs on the inner 55 face of said cap concentrically of said shank and fitting into the depressions, fusible elements carried by said cap corresponding in number with the studs, connections between said elements and studs respectively, a common 60 connection between said elements and shank, and a contact screw adapted to be connected to the other side of the circuit carried by said body and having one end thereof projecting into one of said depressions whereby the fusible elements may be connected in the circuit 65 successively in the rotation of the cap, and tension means acting upon said cap to hold the studs normally in the depressions.

connected in the circuit successively in the rotation of the cap.

2. A multiple fuse plug comprising a body formed centrally with a longitudinal bore and having one end thereof formed 70 with an annular row of depressions concentrically of the bore, a shank within the bore having one end thereof provided with a head forming a contact adapted to be connected to one side of the electric circuit 75 and the opposite end projecting beyond the end of the body having the depressions therein, a cap surrounding the last-mentioned end of said shank concentrically thereof and rotatable thereabout and in face 80 contact with the adjacent end of the body, an annular row of contact studs on the inner face of said cap concentrically of said shank and fitting into the depressions, fusible elements carried by said cap corresponding in number with the studs, connections between said elements and studs respectively, a common connection between said elements and shank, a contact screw adapted to be connected to the other side of the circuit carried by said body and having one end thereof projecting into one of said depressions whereby the fusible elements may be connected in the circuit successively 85 in the rotation of the cap, said common connection comprising a conductor ring carried by said cap concentrically of said shank, and a wire connecting said ring and shank.

3. A multiple fuse plug comprising a body formed centrally with a longitudinal bore and having one end thereof formed 90 with an annular row of depressions concentrically of the bore, a shank within the bore having one end thereof provided with a head 95 forming a contact adapted to be connected to one side of the electric circuit and the opposite end projecting beyond the end of the body having the depressions therein, a cap surrounding the last-mentioned end of said shank concentrically thereof and rotatable thereabout and in face to face contact with the adjacent end of the body, an annular row of contact studs on the inner face of 100 said cap concentrically of said shank and fitting into the depressions, fusible elements carried by said cap corresponding in number with the studs, connections between said elements and studs respectively, a common connection between said elements and shank, a contact screw adapted to be connected to the other side of the circuit carried by said body and having one end thereof projecting into one of the depressions whereby the fusible elements may be connected in the circuit 105 successively in the rotation of the cap, and tension means acting upon said cap to hold the studs normally in the depressions.

4. A multiple fuse plug comprising a body having an annular row of depressions formed in one end concentrically of the axis 110

115 120 125 130

thereof, a cap in face to face contact with said end of the body, an annular row of contact studs on the inner end of said cap and disposed within said depressions, a plurality 5 of fusible elements carried by said cap and connected to said studs respectively, means carried by said body and disposed within one of the depressions therein to engage the stud in such depression and adapted to be 10 connected to one side of an electric circuit, and a connection between the remaining terminals of said fusible elements and the other side of the electric circuit whereby the fusible elements may be connected in the circuit 15 successively as said cap is rotated.

5. A multiple fuse plug comprising a body having an annular row of depressions formed in one end concentrically of the axis thereof, a cap in face to face contact with 20 said end of the body, an annular row of contact studs on the inner end of said cap and

disposed within said depressions, a plurality of fusible elements carried by said cap and connected to said studs respectively, means carried by said body and disposed within 25 one of the depressions therein to engage the stud in such depression and adapted to be connected to one side of an electric circuit, a connection between the remaining terminals of said fusible elements and the other 30 side of the electric circuit whereby the fusible elements may be connected in the circuit successively as said cap is rotated, and a spring holding said cap in engagement with the body and said means in the particular 35 depression.

In testimony whereof I affix my signature in presence of two witnesses.

EMIL STRANSZKY.
